A. VAN HASTE,
WARPING MACHINE,
APPLICATION FILED APR. 18, 1917.

1,244,800.

Patented Oct. 30, 1917.

INVENTOR,
Abram Van Haste.
John Stewart
ATTORNEY.

UNITED STATES PATENT OFFICE.

ABRAM VAN HASTE, OF PATERSON, NEW JERSEY.

WARPING-MACHINE.

1,244,800.

Specification of Letters Patent. Patented Oct. 30, 1917.

Application filed April 18, 1917. Serial No. 162,868.

To all whom it may concern:

Be it known that I, ABRAM VAN HASTE, a citizen of the United States, residing at Paterson, in the county of Passaic and State 5 of New Jersey, have invented certain new and useful Improvements in Warping-Machines, of which the following is a specification.

This invention relates to warping machines, and particularly to so-called Swiss warping machines, in which the warp is laid on the reel in a succession of bands or sections wound thereon spirally, the motion to produce the spiral winding being effected by traversing the reed carriage laterally while the reel is rotating. My invention consists in a novel means for effecting the traverse of the said carriage and yet permitting it to be reset to a new starting point whenever the winding-on of one section is completed and that of another is to begin. My invention further consists in a novel means for gaging the resetting position of the carriage, so that each section may be deposited on the reel in precisely the same spacing from a previously wound section as any other two sections.

In the accompanying drawing,

Figure 1 is a side elevation of a warping machine carriage provided with my improvements, the guide-bars on which it travels and its traversing screw appearing in section;

Fig. 2 is a fragmentary plan of what is shown in Fig. 1, a part of the carriage appearing broken away; and

Fig. 3 is a front elevation, showing the carriage in vertical section on line 3—3 of Fig. 1.

On a guideway formed by the usual pair 40 of guide-rods *a* is arranged to slide the carriage *b*, provided with the usual warp-guiding rollers *c* and reed *d*. *e* is the usual suitably rotated screw whereby the traverse is imparted to the carriage.

In cross-walls of the carriage (designated 45 *a'*) is journaled a front-to-rear extending arbor *f* on which is fixed a worm-wheel *g*, the arbor being kept from longitudinal shifting by the contact of said wormwheel and a collar *h* with the cross-walls, as shown in Fig. 2. The worm-wheel meshes with the screw or worm *e*. Threaded into the top of the carriage at an incline to the arbor is a thumb-screw *i* adapted to bear down on 50 a leather or other suitable plug *j* set in a hole *k* in the carriage so as to bear against the arbor when the thumb-screw is screwed down. When the plug is made to bind against the arbor by means of the thumb-screw, so that the arbor, and hence the 60 worm-wheel, is held from turning, the carriage will be traversed by the rotating screw or worm *e*, and when the plug is released the carriage may be shifted by hand independently of the screw or worm, the arbor then 65 turning with the worm-wheel in its bearings. My construction, thus to obtain a dis- connective connection between the carriage and the worm or screw, is extremely simple; and while a reliable connection between the 70 worm and carriage may be had, the connection may be established or disestablished with the greatest facility and convenience.

In section warping, the start of the lay-ing-on of each new section should begin a 75 definite distance to one side of the start of the preceding section; such distance is usually that between any two threads in a section, and the starting point of each new section is usually on that side of the start- 80 ing point of the preceding section opposite to that from which the traverse proceeds—in other words, if the traverse is from left to right, the resetting of the carriage (from right to left) is such that its new starting 85 point is to the left of its preceding starting point. My means for determining each new starting point with precision is designed to facilitate the gaging and insure against mistakes being made through carelessness 90 or visual errors. On the front rod *a* I place or a collar *l* provided with a set-screw *m* for clamping it at any point on the rod. On a screw *n* in the adjoining side of the carriage an arm *o* is pivoted, and in the arm, pene- 95 trating the same, is arranged a bar *p* which may be shifted in the arm longitudinally (such bar being parallel with the guideway formed by rods *a*) and be held at any point to which it is thus shifted by a set-screw *q* 100 tapped into the arm. The bar penetrates a hole *r* in the side of the carriage, such hole being large enough to permit limited move- 105 ment of the arm on its pivot. The arm may rest on the guide rod when the carriage is spaced from the collar *l* not less than the distance indicated by Fig. 3; if the arm is raised and the carriage or collar moved one toward the other the arm will be supported by bar *p* resting on the collar. At *s* and *t* 110 the gage member formed by the parts *o*—*p*, which is thus in effect stepped, affords

lateral contact faces to bear against the side of the collar.

Suppose the section-width is two inches. Bar p is adjusted in arm o so that its contact face t is two inches from the contact face s of the arm, and there fixed by means of set-screw q . Before starting to wind the first section, the collar l is affixed to the guide rod a so that it abuts the contact face t of the gage member. The first section is then wound. When the winding-on of the first section has been completed, the carriage (having released arbor f and the worm-wheel) is shifted back by hand—
10 to the left—until the contact face s comes to bear against the collar, the gage member being swung up on its pivot to permit this. The carriage will now be at the proper position for starting to wind the second section. Before the second section is started to be wound, however, the collar is released and moved to the left and re-secured to the guide-rod in such position that it abuts the contact face t of the gage member. These
20 operations are repeated on the winding of each section.

The hole r is made large enough only to permit the gage member to be raised sufficiently to permit bar p and not the arm to override the collar, thus to avoid possible errors in gaging. But I do not wish to be restricted to this detail; for, while it is preferred to use the gage so that on the gaging movement of the parts involving the
30 bar p overriding the collar l the gaging contact shall be as between the collar and the face s of the arm, rather than as between the collar and the side of the carriage, this is not essential in the broad aspect of the
35 invention.

It will be understood that the bar is adjusted longitudinally of itself in the arm so that more or less thereof will protrude therefrom toward the collar, according to
40 the width of the sections. In the example given, the section width being two inches, the bar is adjusted so that its end t is two inches from the face s of the arm.

Having thus fully described my invention, what I claim and desire to secure by Letters Patent is:

1. In a warping machine, the combination of a guideway, a carriage member movable along the guideway, means to traverse the carriage, an abutment member settable at stages along the guideway, and a gage ar-

ranged in one of said members and having lateral stepped faces to impinge the other member, said gage being movable in the member carrying it transversely of the guideway to present either face for impingement against the other member.

2. In a warping machine, the combination of a guideway, a carriage member movable along the guideway, means to traverse the carriage member, an abutment member settable at stages along the guideway, and a gage including two parts, one arranged in one member and the other laterally adjustable in the first-named part and said parts
60 having lateral stepped faces to impinge the other member, said gage being movable in the member carrying it transversely of the guideway to present either of said faces for impingement against the other member.

3. In a warping machine, the combination of a guideway, a carriage movable along the guideway, means to traverse the carriage, an abutment member settable at stages along the guideway, and a gage arranged in one of said members and having a lateral face to impinge against the other member, said gage being movable in the member carrying it transversely of the guideway to bring said face out of position to impinge
70 the other member on movement of one of said members toward the other.

4. In a warping machine, the combination of a guideway member, a carriage member movable along the guideway member, means to traverse the carriage member, an abutment member settable at stages along the guideway member, and a gage carried by
80 one of said members and interposed between the carriage and abutment members and movable to clear one of them transversely of the guideway member.

5. In a warping machine, the combination of a guideway member, a carriage member movable along the guideway member, means to traverse the carriage member, an abutment member settable at stages along the guideway member, and a gage carried by
90 one of said members and interposed between the carriage and abutment members and movable to clear one of them transversely of the guideway member, said gage including two parts, one carrying the other and the latter laterally adjustable in the first-named part.

In testimony whereof I affix my signature.
ABRAM VAN HÄSTE.
